United States Patent Office

Des. 215,030

Patented Aug. 19, 1969

215,030

GUITAR

Francis B. Cutright, 52 Prentiss St.,
Munroe Falls, Ohio 44262

Filed Dec. 12, 1968, Ser. No. 14,941

Term of patent 14 years

Int. Cl. D17—03

U.S. Cl. D56—1

I claim:

The ornamental design for a guitar, as shown.
